UNITED STATES PATENT OFFICE.

ROBERT S. PEELLE, OF HOLLIS, NEW YORK, N. Y., ASSIGNOR TO THE PEELLE COMPANY, OF BROOKLYN, NEW YORK, A CORPORATION OF NEW YORK.

ELEVATOR DOOR.

Application filed December 13, 1922. Serial No. 608,722.

To all whom it may concern:

Be it known that I, ROBERT S. PEELLE, a citizen of the United States, residing at Hollis, in the borough of Queens, city of New York, county of Queens, and State of New York, have invented certain new and useful Improvements in Elevator Doors, of which the following is a specification, reference being had therein to the accompanying drawings, which form a part thereof.

My invention relates to elevator doors, and more particularly to an elevator door of the "pass type" wherein the rail structure and the co-operating guide shoes upon the door sections are so constructed and arranged as to permit each door section to have a horizontal component of movement away from the wall of the shaft during its vertical opening movement, and towards the wall of the shaft during its vertical closing movement, no part of the rail structure having any movement in introducing this horizontal component of movement during the vertical movement of the door sections, and the guide shoes carried by the door having no movement independently of the door sections carrying same.

In a door embodying my invention, I employ upon the opposite side bars of the frame of each section of each door, a plurality of guide shoes, one of the shoes upon each section moving upon a rail section independent of that upon which the other shoe has movement, said rail sections being so constructed and arranged as to permit the desired vertical movement of each door section and to impart the desired horizontal component of movement thereto during a portion of this vertical movement, so that a door section, during its opening movement, may pass, or lap, a door section at an adjoining door opening, which last named door section is in the closed position. Each of the sections of each door in its opening movement must cross the plane of movement of a section of a door at an adjacent door opening, thus necessitating the presence of gaps between different guide rail sections, suitable guiding or switch mechanisms being provided for directing the shoes of the door sections co-operating with the different rail sections adjacent such gaps.

The guide rail structure adjacent each door opening in a shaft is like that at the

adjacent door openings, a portion of this rail structure co-operating solely with the door section at the opening adjacent thereto, while other portions co-operate solely with a door section at an adjacent door opening, a condition growing out of the fact that each of the sections of each door has guide shoes upon opposite sides thereof, each having movement along a guide rail section entirely independent of the guide rail section for the other shoe on the same side of said section, thus precluding the use of the guide rail section for the lower door section at one door opening for the upper section of the door at the opening below, which upper section in passing the lower section of the door above must, as to its shoes located adjacent the lintel of that door, move along its own guide rail section to a point above the sill of the door opening immediately above.

The guide rail section for the shoe adjacent the lower edge of the upper door section of a door may, however, co-operate with the lower guide shoe of the lower door section of the door immediately above.

Hence, it will be observed that the guide rail sections adjacent each door opening are so constructed and arranged as to co-operate with the doors at that opening as well as the door sections at the openings above and below same, one section in its use being restricted to co-operate with one door section at the opening with which it is associated and with the other door section at that opening and also with a door section at an adjacent opening; another section being restricted in its use to co-operate with a door section at an adjacent opening; while still another section co-operates with a door section at the opening adjacent which it is located and also with a door section at an adjacent opening.

In an elevator door embodying my invention, the arrangement of the guide rail sections and of the shoes co-operating therewith carried by one door section, is such that at least one shoe of each door section is constantly engaged with a continuous guide rail, and in its movement is not required to cross any gaps, while the other shoe upon that section is so constructed that while it must cross a gap, some portion thereof while crossing such a gap will be engaged with a guide rail or a switch mechanism at each end of the

gap, thus avoiding any possible loss of the operative relation between the guide rail structure and the guide shoes and ensuring its being guided in its movement at all times 5 by positive engagement between the shoes and some part of the guiding means of the guide rail structure.

The construction and arrangement of parts of a door embodying my invention is such 10 that there is no relative movement of any of the parts of the guide rail structure, and the co-operating guide shoes, excepting the sliding movement of the latter with their door sections, thus eliminating substantially 15 all noise beyond that incidental to any elevator door employing vertically and oppositely movable sections; minimizing likelihood of a loss of adjustment of parts such as may occur by the jamming of movable 20 parts, when such are used; and reducing the amount of attention required to keep a door installation in operating condition to a mere occasional greasing of the rails and oiling of the pulleys or sheaves, such as is commonly 25 required with all elevator doors.

The rail structure throughout may be readily assembled in the shop, all of the parts being standardized.

A door embodying my invention lends it 30 self readily to those structural characteristics which permit the stoppage of the lower door section with its reinforced top bar substantially flush with the sill of the door opening, or to the so called truckable feature.

While primarily the door is designed for 35 use in elevator shafts in which the distances between the lintel of one door opening and the sill of the door opening immediately above is insufficient to accommodate the upper door section in this space, it, nevertheless, is apparent that this structure may be 40 readily applied to any shaft irrespective of the spacing of the door openings, and thus avoid the necessity of giving any particular 45 attention to the requirements of the elevator door installation when planning the door openings in a shaft. At the same time a construction embodying my invention will 50 obviate those difficulties arising from varying distances between the lintels and sills of different door openings, a characteristic, however, which is common to all doors of the pass type.

My invention consists primarily in an elevator door embodying therein upper and lower oppositely movable door sections, a rail structure on each side of the openings in an elevator shaft including therein a rail section terminating adjacent the sill and 55 lintel of each door opening, adapted to permit vertical movement of said door sections, and impart a horizontal component of movement thereto during a portion of such vertical movement, a guide shoe adjacent the 60 top of the lower, and adjacent the bottom of

the upper, door section co-operating therewith, a second guide shoe adjacent the top of said upper, and the bottom of said lower, door section, a rail section extending from adjacent the sill of one, to adjacent the 70 lintel of an adjacent, door opening, and co-operating with the second guide shoe on one door section to permit vertical movement of said door section, and to impart a horizontal component of movement thereto during a 75 portion of such vertical movement, a switch mechanism co-operating with the second shoe on the other door section, and a guide rail section extending from adjacent said switch mechanism to a point intermediate 80 the sill and lintel of the adjacent door opening and positioned inwardly of the shaft with relation to said other rail section; and in such other novel features of construction and combination of parts, as are hereinafter 85 set forth and described, and more particularly pointed out in the claims hereto appended.

Referring to the drawings,

Fig. 1 is a condensed view in elevation from within an elevator shaft, showing an elevator door structure embodying my invention;

Fig. 2 is a view of the rail structure at 90 one side of the door opening, with a door structure consisting of two oppositely movable sections shown therein in dotted lines;

Fig. 3 is a front view of a casting forming a part of the rail structure and switch mechanism;

Fig. 4 is a side view thereof;

Fig. 5 is a front view of the guide shoe carried by a door section and co-operating with the switch mechanism, and a guiding rail section associated with said switch mechanism;

Fig. 6 is a side view thereof;

Fig. 7 is a front view of the guide shoe carried by one of the door sections;

Fig. 8 is a side view thereof; and

Figs. 9 and 10 are respectively side and front views of a shoe carried by each of the door sections adjacent the top and the bottom bar of the door frames respectively.

Like letters refer to like parts throughout the several views.

In the embodiment of my invention shown in the drawings, A indicates that wall of an elevator shaft towards the floors of a building, it being a practice in such shafts to have a series of vertically aligned door openings therein, one at each floor. At B I have indicated the sill of one such door opening, at C the lintel of said opening and at D one jamb thereof.

In the drawings, I have shown a portion of the rail structure adjacent one door opening only, it being understood that this structure extends vertically throughout the shaft, the part thereof adjacent each opening be-

ing the same as that adjacent every other opening, so as to provide a continuous rail structure throughout the shaft.

It is also apparent that if desired a pass type door need not be used to close every door opening, this type of door being necessary only where the space between floors is insufficient to receive the door or door section closing the openings at an adjacent 10 floor.

Fireproof freight elevator doors are usually formed of two sections indicated at E and F in the drawings, so connected as to cause said sections to move vertically in 15 opposite directions when opening or closing the door, the connection between the door sections, shown at G in the drawings, passing over a pulley or sheave H, the axis of which is parallel to the wall of the shaft 20 having the door opening therein.

This connection is made upon each side of a door, one end of each connection being secured to a bracket I adjacent the bottom bar of the frame of the upper door 25 section, the other end of said connection being secured to a hanger bar J connected to the lower door section adjacent the top bar of its frame.

This construction of door is old and well 30 known in this art.

The lower section F is provided with a projecting plate, indicated in dotted lines at K in Fig. 2 of the drawings, which forms a part of the trucking feature of the door, 35 and the section E is provided with a projecting angular astragal L adapted to co-operate with said bar K in closing any gap along the meeting line of the two door sections.

Since the means embodying the rail structure carried by the two door sections is the same upon opposite sides of each door opening, in my further description of the invention I will limit myself to an explanation 40 of the details as they exist upon one side of the door openings only, it being understood that this mechanism is duplicated upon the other side. In the drawings, 45 duplicate reference letters are applied to corresponding parts upon opposite sides of the door, it being understood that, particularly as to the guide shoes and switch mechanism, the corresponding parts upon one side of the door are reversed upon the opposite side, 50 these parts being made right and left by reason of their different relations to the guide rail structures upon opposite sides of the door.

While an elevator door of my invention 55 includes a continuous rail structure extending adjacent the opposite jambs of the various door openings in a shaft, this rail structure instead of including a continuous main rail, is formed of a sequence of associated units, one adjacent each door opening, which

units overlap and co-operate in a manner which will more fully appear hereinafter.

Each unit may be the duplicate of every other unit so that a description of but one unit will be necessary. To simplify the description of this unit, it may be considered as consisting of three rail sections and a constantly open switch mechanism for directing a shoe moving with a door section from a rail section adjacent one door opening to a co-operating rail section at the adjacent door opening so as to impart to the portion of the door adjacent said shoe, that horizontal component of movement during a portion of the vertical movement, to bring it from a vertical plane adjacent the wall of the shaft at one door opening to a vertical plane at a point more remote therefrom in the shaft, at an adjacent door opening so as to permit it to pass a closed door at that opening.

The rail structure includes a wall angle, one flange a' of which is secured to the wall of the shaft adjacent each jamb of each door opening and extends vertically throughout the shaft, the other flange a of this angle extending inwardly of the shaft, and having secured thereto various rail sections and switch mechanisms.

One of the rail sections above referred to 95 includes therein a short vertical rail length b extending intermediate the sill B and lintel C for a short distance upon opposite sides of the parting line of the two door sections E and F when the door is in the 100 closed position. This section is so positioned as to hold the meeting edges of the door sections sufficiently close to the wall of the shaft when the door is closed.

Spaced within the shaft away from said rail length b are two rail lengths $c-d$ parallel therewith, one of which terminates adjacent the sill and the other of which adjacent the lintel, the length b being connected to said lengths c and d respectively by the oblique rail lengths e and f . The rail lengths c and d are in substantially the same vertical plane. This rail section formed of the lengths c , d , e and f is adapted to co-operate with both door sections E and F 110 at a door opening, the rail length c being also adapted to co-operate with the lower door section at the adjacent shaft opening. The upper door section E adjacent the bottom bar of the frame thereof, is provided 115 with a guide shoe g co-operating with a portion of the rail length b , the oblique rail length e and the rail length c , while the top of the lower door section F is provided 120 with a similar guide shoe h adapted to co-operate with the rail lengths b , f and d .

The shoe g preferably has oppositely disposed flanges g' and g^2 thereon having a space between same, the opposite ends of 125 said space being flared to reduce the fric-

tion area of the shoe and being so formed as to afford substantially parallel faces g^3 and g^4 extending substantially vertically, so as to readily co-operate with the vertically extending rail lengths, and parallel oblique faces g^5 and g^6 adapted to co-operate with the oblique rail sections respectively. The shoe h is of the same construction and arrangement as the shoe g , having the flanges h^1 and h^2 , vertical parallel sections h^3 and h^4 , and the spaced oblique sections h^5 and h^6 . The relation of these parts, however, is reversed by reason of the fact that the door section carrying said shoe moves in a direction opposite to that of the section carrying the shoe g .

A second rail section consisting of a short length i adjacent the sill B , a rail length j terminating adjacent the lintel of an adjacent door opening, and an oblique connecting rail section k connecting the sections i and j , is, with the rail length c at the adjoining door opening, adapted to co-operate with the lower door section in guiding it in its vertical movement and imparting a horizontal component of movement thereto during a portion of this vertical movement. The rail length i is arranged on substantially the same vertical plane as the rail length b , while the rail length j is on substantially the same vertical plane as the rail lengths c and d , the oblique connecting rail length k being substantially parallel with the oblique rail length f .

The lower door section is provided with a guide shoe m preferably consisting of two parallel flanges m^1 and m^2 which are spaced apart a distance substantially corresponding with the width of the guide rail length $i-j-k$, the adjacent ends of these flanges lapping each other slightly so as to afford elongated bearing surfaces while permitting oblique clearance between the two flanges sufficient to permit the passage of the shoe over the oblique connecting rail length k without tilting action on the door. The staggered relation of the flanges m^1 and m^2 will ensure a continued engagement of one of these parts with the rail length j until after the other flange as m^2 has engaged the rail length c at an adjacent door opening, or a part of the switch mechanism between these rail lengths, which switch mechanism will be more fully referred to hereinafter.

The third rail section consists of a single rail length n , one end of which terminates adjacent the lintel of one door opening and the other end of which terminates adjacent the end of the rail length d at the opening above. This rail section n co-operates solely with the upper door section and extends substantially parallel with the rail lengths d and j but spaced therefrom inwardly of the shaft to afford clearance for

the guide shoes of the lower door section at the door opening above. The use of the rail section n is necessitated from the fact that the upper door section in its ascent must pass the lower door section of the opening immediately above when said last named door section is in the closed position, and because neither the rail lengths j nor d can be utilized for this purpose without the formation of a gap between the rail lengths j and k to permit the upper guide shoe on the upper section of a door at an opening below that at which the rail lengths $j-d$ are located, to pass from the length j at one opening to the length d at that opening. Otherwise the upper section of a door at a lower opening would move along the oblique connecting section k , which it is apparent would cause it to collide with the lower door section of the door immediately above it.

When it is desired to provide independent guide rails for the different shoes upon each door section, such a gap is undesirable at the point indicated, particularly as a gap must be provided at a switch mechanism situated at a point where the lower door section is having only vertical movement, and the shoe on this section being specially formed to span this gap and not adapted for the making of an oblique turn at, or during, that interval in which the door is receiving the horizontal component of movement to bring it to a vertical plane which will allow it to move inwardly of the shaft so as to pass by a closed door at another door opening.

While the lower guide shoe g of the door section E co-operates with the rail lengths b , d and c of the rail section opposite the door opening, (and not extending materially beyond same) the upper guide shoe o upon this door section does not engage the aforesaid rail lengths but co-operates solely with the rail section n and a switch mechanism p adjacent the lintel of the door opening. This switch mechanism has the two-fold function of engaging said shoe so as to hold the upper portion of the door close to the wall of a shaft when in the closed position, and guiding said shoe during the opening movement of the door in its vertical movement, while imparting the desired horizontal component to such movement to bring the shoe into engagement with the rail section n . This switch mechanism must also be so constructed as to permit the passage of the guide shoe m from a rail length d to a rail length c during a solely vertical movement, a gap indicated at q being provided to permit a shoe o upon a door section E to cross the plane of movement of a shoe m upon a door section F at an adjacent floor.

The shoe o comprises a flange o^1 having a substantially flat surface at o^2 which in the

operation of the shoe is adapted to engage the flange a' of the wall angle, adjacent the lintel of a door, and a curved surface o^3 adapted to engage one face of the rail section n and a curved surface o^4 adapted to engage a guide abutment of the switch mechanism. Spaced away from the flange o' is a second flange o^5 which extends laterally of the shoe and is provided with a curved surface o^6 forming a flaring opening having a cam-like surface at one side thereof, an inclined surface o^7 adapted to co-operate with the switch mechanism during the closing movement of the door section, and a flattened end o^8 parallel with the surface o^2 on the flange o' .

The switch mechanism includes a guide flange p^2 adapted to be engaged by the surface o^8 on the flange o^5 , and a curved fixed 20 abutment p' adapted to co-operate with the curved surface o^4 on the flange o' , the flange p^2 and abutment p' having parallel curved surfaces indicated at p^3 and p^4 respectively, the channel between which is directed above 25 and across the rail length c and into the gap q between said rail length and the lower end of the rail length n . Upon the other side of the gap q opposite the upper end of the abutment p' , is a second abutment r , 30 having a surface r' parallel with the rails c and j , and a curved surface r^2 presented towards the end of the rail length n , and positioned at one side of and between said rail and the end of the rail length c , and being 35 on approximately the same radius as the curved surface p^3 .

The end of the section n terminates at a point of the gap q intermediate the rail lengths c and j inwardly of the shaft as to 40 these rail sections, so as to permit the passage of the shoe m from the rail section j to the rail length c without engaging the rail n , the abutment r or the abutment p' , which last named abutment terminates at 45 one side of the gap between the rail lengths c and j and the wall of the shaft.

To ensure accuracy in the formation and the arrangement of the ends of the rail lengths c , j and n of the flange p^2 , the abutment p' and the abutment r , I preferably 50 form these parts in a single casting, thus permitting the standardization of parts, and very much simplifying the assembling of the structure.

The flange a' of the wall angle is cut away at a^2 substantially flush with the rail lengths b , e and f so as to form a recess conforming in contour to the angular relation of these parts, thus permitting the hanger bar J and the brackets I to move toward and from the wall of the shaft during that interval when the guide shoes g and h are passing along the rail lengths b , e and f .

At s I have indicated a flame angle extending vertically of each side bar of the

frame of each door section adjacent the flange a of the wall angle, said flame angle being of a depth to pass across the edges of the various rail sections and of the switch mechanism, and at t a flame angle and toe 70 guard upon the lower door section F .

Secured to the flanges a' of the wall angles, adjacent and below the sill of each door opening, are stops u adapted to be engaged by the hanger bar J when the door is 75 in the fully open position, so as to hold the reinforced top of this section substantially flush with the sill B .

The operation of the herein described mechanism is substantially as follows:— 80

When a door is in the closed position, the shoes g and h upon the respective door sections E and F , will engage the short rail length b adjacent the meeting edges 85 of these door sections and hold this portion of said door sections close to the wall of the shaft at the door opening. The shoe o will be positioned as shown in Fig. 2 between the guide flange p^2 of the switch mechanism and the flange a' of the wall 90 angle, the flattened surface o^8 of the flange o^5 engaging a straight portion of the flange p^2 while the flat portion o^2 of the flange o' will engage said wall angle flange, thus holding the upper portion of the door section 95 E close to the wall of the shaft and against movement inwardly of the shaft. The flanges m' and m^2 of the shoe m will engage opposite faces of the short rail length i , holding the lower portion of the door section F close 100 to the wall of the shaft. In this manner both sections of the door when it is closed will be arranged in the same vertical plane close to the wall of the shaft A and present no such cracks or crevices as 105 would introduce a fire hazard in the door structure.

When opening a door, the sections E and F move in opposite directions, one upwardly and the other downwardly, said door sections, during a portion of their vertical movement, having a horizontal component of movement to an extent slightly greater than the thickness of the door, so as to permit them to pass similar doors at the openings above and below that opening closed by the door being opened. 115

While the movement of the two door sections is similar, the means for securing this movement differ with each section, so that the movement of each door section will be described separately, it being understood, however, that the movements of the different sections occur at substantially the same time. 120

Referring to the lower door section F , as 125 this section moves downwardly, the parallel faces h^3 and h^4 on the shoe h will pass along the vertically extending rail length b until the lower edge of said shoe approaches the end of said rail length b , whereupon the oblique 130

surfaces h^5 and h^6 of said shoe will engage the oblique rail length f , the surface h^5 engaging the upper face of said rail length, and thus impart the desired horizontal component of movement to that portion of the door until said inclined surface passes from the rail length f , whereupon the surfaces h^3 and h^4 will engage and pass along the rail length d until the hanger bar J engages the stops u , or until the door is brought to rest with the top thereof substantially flush with the sill D by said stops or other means used in lieu thereof.

During the descent of the door section F , the flanges m' and m^2 of the shoe m will pass along opposite sides of the rail length i until the end of the flange m^2 engages the upper face of the oblique rail length k , whereupon the lower portion of the section will receive a horizontal component of movement during the continued downward vertical movement, until said flange m^2 passes from the oblique rail length k to along the side of the rail length j which will be received between the spaced parallel flanges m' and m^2 . Since the flange m' is positioned below the flange m^2 , it will project across the gap q and engage one side of the rail length c at the door opening below that by which the moving door is closed, being positioned between the rail length c and the abutment p' so as to prevent movement of the door toward the wall of the shaft. This engagement with said rail length c prevents movement of the door section inwardly of the shaft. After the flange m' passes from its engaging relation with the abutment p' , the guide flange p^2 will still prevent inward movement of the door section until the flange m^2 has engaged the opposite side of the rail length c .

As to the upper door section E , with the initial opening movement thereof, the shoe g will act in relation to the rail lengths b , e and c in exactly the same manner as the corresponding parts of the shoe h of the lower door section, so that this mode of operation need not be described.

With the upward movement of the door section E , the surfaces o^2 of the flange o' and o^8 of the flange o^5 will slide along the parallel portions of the guide flange p^2 and the wall angle flange a' until the curved surface o^4 upon the flange o' engages the curved surface of the abutment p' which will impart a horizontal component of movement to said door section E and direct the flanges o' and o^5 to a position where they will receive between them, the end of the rail section n . The abutment r will check any tendency of an excess movement of the shoe o inwardly of the shaft and ensure said shoe passing upon the rail length n . Thereafter while the shoe g is passing along the rail length c , the shoe o will pass along the rail

length n , thus bringing the door section E inwardly of the shaft to the same extent as the door section F , so that the upper door section E will be in a position to pass the lower door section F at the floor immediately above. 70

While the rail length $-n$ is located within the shaft to a greater extent than the rail length c , the difference is merely that sufficient to accommodate the shoe flange o' 75 and in a door section which is four or six feet in height, this distance, which is but a fraction of an inch, will have no material effect upon the movements of the door, as the clearance between the shoes and the 80 rails would of necessity be sufficient to permit that very slight tilting action which might result from this location of the rail length n .

In closing a door, the shoes h and g will 85 operate in a manner the reverse of that above described, the oblique sections h^5 and g^6 bearing upon the lower and the upper faces of the oblique lengths f and e respectively for imparting the return horizontal 90 movement to the doors, and the end of the flange m' engaging the lower face of the oblique section k in imparting the desired horizontal movement to the lower part of the door section F . 95

When passing the switch mechanism, the upper flange m^2 will pass the abutment r and the end of the rail length n — before the flange m' passes from the guide flange p^2 and the abutment p' , and the flange m^2 100 engaging the rail length d before the flange m' has passed from engagement with the rail length c .

During the ascent of the door section F , the upper door section E will descend, the shoe o passing along the rail length n until the inclined plane face o^7 of the guide flange o^5 engages the abutment r which directs the shoe o toward the shaft A passing the top of the rail length c and engaging 105 the curved end p^3 of the guide flange p^2 substantially simultaneously with the engagement of the curved surface o^4 of the flange o' with the curved surface p^4 of the abutment p' . 110

As shown in the drawings, the end of the rail n is curved slightly and reduced to an edge to facilitate the engagement and disengagement thereof with the laterally extended flange o^5 , the ends of the rail lengths j , c and of the guide flange p^3 also being rounded or reduced to an edge to minimize likelihood of the guide shoes abutting against same and ensuring a free sliding movement between these parts and the shoe co-operating therewith. 115

It will be observed that the various guide flanges and abutments constituting the normally open switch are not only so constructed and arranged as to permit this 120 125 130 135

switch mechanism to co-operate either with the guide shoe *m* of a door section at one door opening, and the guide shoe *o* of a door section at a door immediately below same, but that all of the co-operating parts of the switch mechanism and the guide shoe occupy a fixed position so as to ensure uniformity in the operation of the doors at all times, and avoid any likelihood of a breakage or disarrangement of parts.

The guide shoe *o* will pass transversely of the gap *q*, crossing the plane of the rail sections *j* and *c*, the lateral deflection of the flange *o'* ensuring the engagement of the surface *o''* thereof with the face of the rail length *n* presented inwardly of the shaft during the upward movement of the door section, and the engagement of the inclined flat surface *o''* of said flange with the abutment *r* with the downward movement of said section, and will serve to guide the movements of the shoe *o* and the portion of the door section adjacent thereto during such movements until the other flange *o'* has engaged either the rail *n* or the fixed abutment *p'*.

The arrangement of parts is such that the various guide shoes are always in such engaging relation with the rail structure as to ensure positive opening and closing movement of both door sections, and that such movement, by reason of this continued engagement, without the movement of any parts except a free sliding movement of the shoe with relation to the parts of the rail structure with the movement of the door itself, will be practically noiseless.

By employing co-operating curved surfaces upon the abutment *p'* and *r* upon the guide flange *p''*, and upon the flanges *o'* and *o''* upon the shoe *o*, greater ease in the movement of the door and less noise is assured, although it is apparent that straight inclined co-acting surfaces upon these parts would secure the same operative effect, but with slight jars during the movement of the door upon the initial engagement of these parts either during their upward or downward movement.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:

1. An elevator door embodying therein upper and lower oppositely movable door sections, a rail structure on each side of the openings in an elevator shaft including therein a rail section terminating adjacent the sill and lintel of each door opening, adapted to permit vertical movement of said

door sections, and impart a horizontal component of movement thereto during a portion of such vertical movement, a guide shoe adjacent the top of the lower, and adjacent the bottom of the upper, door section co-operating therewith, a second guide shoe adjacent the top of said upper, and the bottom of said lower, door section, a rail section extending from adjacent the sill of one, to adjacent the lintel of an adjacent, door opening, and co-operating with the second guide shoe on one door section to permit vertical movement of said door section, and to impart a horizontal component of movement thereto during a portion of such vertical movement, a switch mechanism co-operating with the second shoe on the other door section, and a guide rail section extending from adjacent said switch mechanism to a point intermediate the sill and lintel of the adjacent door opening and positioned inwardly of the shaft with relation to said other rail section.

2. An elevator door embodying therein upper and lower oppositely movable door sections, a rail structure on each side of the openings in an elevator shaft including therein a rail section including therein a short rail length intermediate the sill and lintel of a door opening, long rail lengths parallel therewith positioned inwardly of the shaft with relation thereto, and oblique connecting rail lengths, a guide shoe adjacent the bottom of the upper, and adjacent the top of the lower, door section co-operating therewith, a rail section extending from adjacent the sill of one, to adjacent the lintel of an adjacent, door opening, including a short rail length in substantially the same plane as said first named short rail length, a long rail length parallel therewith and in substantially the same plane as said first named long rail lengths, and an oblique connecting rail length, a second guide shoe co-operating with said

last named rail section comprising oppositely disposed staggered parallel flanges, having the adjacent ends thereof lapped to conform to said last named oblique rail length, a switch mechanism between the lintel of one door opening and the sill of the opening above, a second guide shoe upon said other door section co-operating with said switch mechanism, and a guide rail section extending from adjacent said

switch mechanism to a point intermediate the sill and lintel of the adjacent door opening and positioned inwardly of the shaft with relation to said other rail sections.

3. An elevator door embodying therein upper and lower oppositely movable door sections, a rail structure on each side of the openings in an elevator shaft including therein a rail section including there-

- in a short rail length intermediate the sill and lintel of a door opening, long rail lengths parallel therewith positioned inwardly of the shaft with relation thereto, 5 and oblique connecting rail lengths, a guide shoe on one of said sections comprising spaced flanges having parallel faces adapted to co-operate with the parallel rail lengths, and parallel oblique faces adapted to co- 10 operate with the oblique connecting rail length, a switch mechanism between the lintel of one door opening and the sill of an adjacent opening, a guide rail section extending from adjacent said switch mechanism to a point intermediate the sill and 15 lintel of the adjacent door opening and positioned inwardly of the shaft with relation to said first named rail structure, a second guide shoe upon said door section 20 co-operating with said switch mechanism and said last named guide rail section, a guide shoe upon the other door section co-operating with said first named rail structure, a rail section extending from adjacent 25 the sill of one, to adjacent the lintel of an adjacent, door opening, adapted to permit vertical movement of the adjacent door section and to impart a horizontal component of movement thereto during a portion of 30 such vertical movement, and a second shoe upon said last named door section co-operating with said last named rail section. 4. An elevator door embodying therein upper and lower oppositely movable door 35 sections, a rail structure on each side of the openings in an elevator shaft including therein a rail section comprising a short rail length intermediate the sill and lintel of a door opening, long rail lengths parallel therewith positioned inwardly of the shaft with relation thereto, and oblique connecting rail lengths, a rail section extending from adjacent the sill of one, to adjacent the lintel of an adjacent, door opening, including a short rail length in substantially the same plane as said first named short rail length, a long rail length parallel therewith and in substantially the same plane as said first named long rail lengths, but spaced therefrom to form a gap, and an oblique connecting rail length, a switch mechanism between the lintel of one door opening and the sill of the opening above, comprising means forming a channel, one end of which is directed across said gap, a guide rail section extending from adjacent said end of said channel to a point intermediate the sill and lintel of the adjacent door opening and positioned inwardly of the shaft with relation to said other rail sections, guide shoes upon said door sections each co-operating with the short rail length and with a long rail length and with an oblique connecting rail length of said first named rail section, a guide shoe on one of said door sections co-operating with the rail section extending from adjacent the sill of one door opening to adjacent the lintel of an adjacent door opening and a long rail length at an adjacent door opening, and a guide shoe upon the other door section comprising parallel spaced flanges adapted to engage the opposite walls of said channel forming means, and receive between same the rail length terminating adjacent the end of said channel. 6. An elevator door embodying therein upper and lower oppositely movable door sections, a rail structure on each side of the openings in an elevator shaft including therein a rail section comprising a short rail length intermediate the sill and lintel of a door opening, long rail lengths parallel spaced flanges having

therewith positioned inwardly of the shaft with relation thereto, and oblique connecting rail lengths, a rail section extending from adjacent the sill of one, to adjacent the lintel of an adjacent, door opening, including a short rail length in substantially the same plane as said first named short rail length, a long rail length parallel therewith and in substantially the same plane as said first 5 named long rail lengths, but spaced therefrom to form a gap, and an oblique connecting rail length, a switch mechanism between the lintel of one door opening and the sill of the opening above, comprising means 10 forming a channel, one end of which is directed across said gap, a guide rail section extending from adjacent said end of said channel to a point intermediate the sill and lintel of the adjacent door opening and positioned inwardly of the shaft with relation to said other rail sections, guide shoes upon said door sections each co-operating with the short rail length and with a long rail length and with an oblique connecting rail length 15 of said first named rail section, a guide shoe on one of said door sections co-operating with the rail section extending from adjacent the sill of one door opening to adjacent the lintel of an adjacent door opening and a long rail length at an adjacent door opening, and a guide shoe upon the other door section comprising parallel spaced flanges, one of said flanges being projected laterally of the shoe and having a curved surface forming a flaring opening for the space between said flanges, an inclined surface and a flattened end, and the other of said flanges having a substantially 20 flat surface, and vertically and laterally extending curved surfaces, whereby said shoe is adapted to engage the opposite walls of said channel forming means, and receive between same the rail length terminating adjacent the end of said channel. 25

6. An elevator door embodying therein upper and lower oppositely movable door sections, a rail structure on each side of the openings in an elevator shaft including therein a rail section comprising a short rail length intermediate the sill and lintel of a door opening, long rail lengths parallel therewith positioned inwardly of the shaft with relation thereto, and oblique connecting rail lengths, a rail section extending from adjacent the sill of one, to adjacent the 30 lintel of an adjacent, door opening, including a short rail length in substantially the same plane as said first named short rail length, a long rail length parallel therewith and in substantially the same plane as said first 35 named long rail lengths, but spaced therefrom to form a gap, and an oblique connecting rail length, a switch mechanism between the lintel of one door opening and a long rail length at an adjacent door opening, and a guide shoe upon the other door section comprising parallel spaced flanges, one of said flanges being projected laterally of the shoe and having a curved surface forming a flaring opening for the space between said flanges, an inclined surface and a flattened end, and the other of said flanges having a substantially 40 flat surface, and vertically and laterally extending curved surfaces, whereby said shoe is adapted to engage the opposite walls of said channel forming means, and receive between same the rail length terminating adjacent the end of said channel. 45

7. An elevator door embodying therein upper and lower oppositely movable door sections, a rail structure on each side of the openings in an elevator shaft including therein a rail section comprising a short rail length intermediate the sill and lintel of a door opening, long rail lengths parallel therewith positioned inwardly of the shaft with relation thereto, and oblique connecting rail lengths, a rail section extending from adjacent the sill of one, to adjacent the 50 lintel of an adjacent, door opening, including a short rail length in substantially the same plane as said first named short rail length, a long rail length parallel therewith and in substantially the same plane as said first 55 named long rail lengths, but spaced therefrom to form a gap, and an oblique connecting rail length, a switch mechanism between the lintel of one door opening and the sill of the opening above, comprising means forming a channel, one end of which is directed across said gap, a guide rail section extending from adjacent said end of said channel to a point intermediate the sill and lintel of the adjacent door opening and positioned inwardly of the shaft with relation to said other rail sections, guide shoes upon one of said door sections, one of which 60 co-operates with the short rail length and 65 flange adjacent the end of one of the long

with a long rail length and with an oblique connecting rail length of said first named rail section, and the other of which co-operates with the rail section extending from 5 adjacent the sill of one door opening to adjacent the lintel of an adjacent door opening and a long rail length at an adjacent door opening, a guide shoe upon the other door section comprising spaced flanges having 10 parallel faces adapted to co-operate with the short rail length and a long rail length of said first named rail section, and parallel oblique faces adapted to co-operate with an oblique connecting rail length of said rail section, and a guide shoe upon the other door section comprising parallel spaced flanges, one of said flanges being projected laterally of the shoe and having a curved surface forming a flaring opening for the space between 15 said flanges, an inclined surface and a flattened end, and the other of said flanges having a substantially flat surface, and vertically and laterally extending curved surfaces, whereby said shoe is adapted to engage the opposite walls of said channel forming means, and receive between same the rail length terminating adjacent the end of said channel.

9. An elevator door embodying therein 30 upper and lower oppositely movable door sections, a rail structure on each side of the openings in an elevator shaft including therein a rail section comprising a short rail length intermediate the sill and lintel of a 35 door opening, long rail lengths parallel therewith positioned inwardly of the shaft with relation thereto, and oblique connecting rail lengths, a rail section extending from adjacent the sill of one, to adjacent the lintel 40 of an adjacent, door opening, including a short rail length in substantially the same plane as said first named short rail length, a long rail length parallel therewith and in substantially the same plane as said first 45 named long rail lengths, but spaced therefrom to form a gap, and an oblique connecting rail length, a switch mechanism between the lintel of one door opening and the sill of the opening above, comprising a guide flange 50 adjacent the end of one of the long rail lengths of said first named rail section, an abutment between the wall of the shaft and said guide flange and spaced therefrom, said guide flange and said abutment being so 55 formed as to provide a channel therebetween, one end of which is directed across said gap, and an abutment located substantially opposite the end of said channel beyond, and having a curved surface presented 60 towards, said gap, a guide rail section extending from adjacent said end of said channel to a point intermediate the sill and lintel of the adjacent door opening and positioned inwardly of the shaft with relation to 65 said other rail sections, guide shoes upon

said door sections each co-operating with the short rail length and with a long rail length and with an oblique connecting rail length of said first named rail section, a guide shoe on one of said door sections co-operating 70 with the rail section extending from adjacent the sill of one door opening to adjacent the lintel of an adjacent door opening and a long rail length at an adjacent door opening, and a guide shoe upon the other door section comprising parallel spaced flanges, one of said flanges being projected laterally of the shoe and having a curved surface forming a flaring opening for the space between said flanges, an inclined surface and a flattened end, and the other of 75 said flanges having a substantially flat surface, and vertically and laterally extending curved surfaces, whereby said shoe is adapted to engage the opposite walls of said channel forming means, and receive between same the rail length terminating adjacent the end of said channel.

10. An elevator door embodying therein 90 upper and lower oppositely movable door sections, a rail structure on each side of the openings in an elevator shaft including therein a rail section comprising a short rail length intermediate the sill and lintel of a 95 door opening, long rail lengths parallel therewith positioned inwardly of the shaft with relation thereto, and oblique connecting rail lengths, a rail section extending from adjacent the sill of one, to adjacent the lintel of an adjacent, door opening, including a short rail length in substantially the same plane as said first named short rail length, a long rail length parallel therewith and in substantially the same plane as said first 100 named long rail lengths, but spaced therefrom to form a gap, and an oblique connecting rail length, a switch mechanism between the lintel of one door opening and the sill of the opening above, comprising 105 means forming a channel, one end of which is directed across said gap, a guide rail section extending from adjacent said end of said channel to a point intermediate the sill and lintel of the adjacent door opening and positioned inwardly of the shaft with relation to 110 said other rail sections, guide shoes upon said door sections each co-operating with the short rail length and with a long rail length and with an oblique connecting rail length of said first named rail section, a 115 guide shoe on one of said door sections comprising oppositely disposed staggered parallel flanges having the adjacent ends thereof lapped, whereby the parallel faces thereof are adapted to co-operate with the parallel rail lengths, and the lapped ends are adapted to co-operate with the oblique connecting rail 120 length of the rail section extending from adjacent the sill of one door opening to adjacent the lintel of an adjacent door opening to 125 adjacent the lintel of an adjacent door opening to 130

ing and a long rail length at an adjacent door opening, and a guide shoe upon the other door section comprising parallel spaced flanges adapted to engage the opposite walls of said channel forming means, and receive between same the rail length terminating adjacent the end of said channel.

11. An elevator door embodying therein upper and lower oppositely movable door sections, a rail structure on each side of the openings in an elevator shaft including therein a rail section comprising a short rail length intermediate the sill and lintel of a door opening, long rail lengths parallel therewith positioned inwardly of the shaft with relation thereto, and oblique connecting rail lengths, a rail section extending from adjacent the sill of one, to adjacent the lintel of an adjacent, door opening, including a short rail length in substantially the same plane as said first named short rail length, a long rail length parallel therewith and in substantially the same plane as said first named long rail lengths, but spaced therefrom to form a gap, and an oblique connecting rail length, a switch mechanism between the lintel of one door opening and the sill of the opening above, comprising means forming a channel, one end of which is directed across said gap, a guide rail section extending from adjacent said end of said channel to a point intermediate the sill and lintel of the adjacent door opening and positioned inwardly of the shaft with relation to said other rail sections, a guide shoe upon one of said door sections comprising spaced flanges having parallel faces adapted to co-operate with the short rail length and a long rail length of said first named rail section, and parallel oblique faces adapted to co-operate with an oblique connecting rail length of said first named rail section, a guide shoe on one of said door sections comprising oppositely disposed staggered parallel flanges having the adjacent ends thereof lapped, whereby the parallel faces thereof are adapted to co-operate with the parallel rail lengths, and the lapped ends are adapted to co-operate with the oblique connecting rail length of the rail section extending from adjacent the sill of one door opening to adjacent the lintel of an adjacent door opening and a long rail length at an adjacent door opening, a guide shoe upon the other door section co-operating with the short rail length, a long rail length and an oblique connecting rail length of said first named rail section, and a second guide shoe upon said door section comprising parallel spaced flanges adapted to engage the opposite walls of said channel forming means, and receive between same the rail length terminating adjacent the end of said channel.

12. An elevator door embodying therein upper and lower oppositely movable door

sections, a rail structure on each side of the openings in an elevator shaft including therein a rail section comprising a short rail length intermediate the sill and lintel of a door opening, long rail lengths parallel therewith positioned inwardly of the shaft with relation thereto, and oblique connecting rail lengths, a rail section extending from adjacent the sill of one, to adjacent the lintel of an adjacent, door opening, including a short rail length in substantially the same plane as said first named short rail length, a long rail length parallel therewith and in substantially the same plane as said first named long rail lengths, but spaced therefrom to form a gap, and an oblique connecting rail length, a switch mechanism between the lintel of one door opening and the sill of the opening above, comprising means forming a channel, one end of which is directed across said gap, a guide rail section extending from adjacent said end of said channel to a point intermediate the sill and lintel of the adjacent door opening and positioned inwardly of the shaft with relation to said other rail sections, a guide shoe upon one of said door sections comprising spaced flanges having parallel faces adapted to co-operate with the short rail length, and with a long parallel rail length, and parallel oblique faces adapted to co-operate with an oblique connecting rail length of said first named rail section, a guide shoe on one of said door sections comprising oppositely disposed staggered parallel flanges having the adjacent ends thereof lapped, whereby the parallel faces thereof are adapted to co-operate with the parallel rail lengths, and the lapped ends are adapted to co-operate with the oblique connecting rail length of the rail section extending from adjacent the sill of one door opening to adjacent the lintel of an adjacent door opening and a long rail length at an adjacent door opening, and a guide shoe upon the other door section comprising parallel spaced flanges adapted to engage the opposite walls of said channel forming means, and receive between same the rail length terminating adjacent the end of said channel.

13. An elevator door embodying therein upper and lower oppositely movable door sections, a rail structure on each side of the openings in an elevator shaft including therein a rail section comprising a short rail length intermediate the sill and lintel of a door opening, long rail lengths parallel therewith positioned inwardly of the shaft with relation thereto, and oblique connecting rail lengths, a rail section extending from adjacent the sill of one, to adjacent the lintel of an adjacent, door opening, including a short rail length in substantially the same plane as said first

- named short rail length, a long rail length parallel therewith and in substantially the same plane as said first named long rail lengths, but spaced therefrom to form a 5 gap, and an oblique connecting rail length, a switch mechanism between the lintel of one door opening and the sill of the opening above, comprising a guide flange adjacent the end of one of the long rail lengths of said 10 first named rail section, and an abutment between the wall of the shaft and said guide flange and spaced therefrom, said guide flange and said abutment being so formed as to provide a channel therebetween, one 15 end of which is directed across said gap, a guide rail section extending from adjacent said end of said channel to a point intermediate the sill and lintel of the adjacent door opening and positioned inwardly of 20 the shaft with relation to said other rail sections, guide shoes upon said door sections each comprising spaced flanges having parallel faces adapted to co-operate with the short rail length and with a long parallel 25 rail length, and parallel oblique faces adapted to co-operate with an oblique connecting rail length of said first named rail section, a second guide shoe on one of said door sections comprising oppositely disposed 30 staggered parallel flanges having the adjacent ends thereof lapped, whereby the parallel faces thereof are adapted to co-operate with the parallel rail length, and the lapped ends are adapted to co-operate with the 35 oblique connecting rail length of the rail section extending from adjacent the sill of one door opening to adjacent the lintel of an adjacent door opening, and a long rail length at an adjacent door opening, and a 40 guide shoe upon the other door section comprising parallel spaced flanges, one of said flanges being projected laterally of the shoe and having a curved surface forming a flaring opening for the space between said 45 flanges, an inclined surface and a flattened end, and the other of said flanges having a substantially flat surface, and vertically and laterally extending curved surfaces, whereby said shoe is adapted to engage the 50 opposite walls of said channel forming means, and receive between same the rail length terminating adjacent the end of said channel.
14. An elevator door embodying therein 55 upper and lower oppositely movable door sections, a rail structure on each side of the openings in an elevator shaft including therein a rail section comprising a short rail length intermediate the sill and lintel 60 of a door opening, long rail lengths parallel therewith positioned inwardly of the shaft with relation thereto, and oblique connecting rail lengths, a rail section extending from adjacent the sill of one, to adjacent the 65 lintel of an adjacent, door opening, a switch mechanism, and a guide rail section extend- 70 75 80 85 90 95 100 105 110 115 120 125 130
- opening, including a short rail length in substantially the same plane as said first named short rail length, a long rail length parallel therewith and in substantially the same plane as said first named long rail lengths, but spaced therefrom to form a gap, and an oblique connecting rail length, a switch mechanism between the lintel of one door opening and the sill of the opening above, comprising a guide flange adjacent the end of one of the long rail lengths of said first named rail section, and an abutment between the wall of the shaft and said guide flange and spaced therefrom, said guide flange and said abutment being so formed as to provide a channel therebetween, one end of which is directed across said gap, a guide rail section extending from adjacent said end of said channel to a point intermediate the sill and lintel of the adjacent door opening and positioned inwardly of the shaft with relation to said other rail sections, said abutment, said guide flange and the ends of the various rail lengths adjacent thereto being integrally formed in a metal casting, guide shoes upon said door sections each co-operating with the short rail length and with a long rail length and with an oblique connecting rail length of said first named rail section, a guide shoe on one of said door sections co-operating with the rail section extending from adjacent the sill of one door opening to adjacent the lintel of an adjacent door opening and a long rail length at an adjacent door opening, and a guide shoe upon the other door section comprising parallel spaced flanges, one of said flanges being projected laterally of the shoe and having a curved surface forming a flaring opening for the space between said flanges, an inclined surface and a flattened end, and the other of said flanges having a substantially flat surface, and vertically and laterally extending curved surfaces, whereby said shoe is adapted to engage the opposite walls of said channel forming means, and receive between same the rail length terminating adjacent the end of said channel.
15. An elevator door embodying therein upper and lower oppositely movable door sections, a rail structure on each side of the openings in an elevator shaft, each consisting of a wall angle extending vertically of the shaft and having secured thereto a rail section including therein a short rail length intermediate the sill and lintel of the door opening; long rail lengths parallel therewith positioned inwardly of the shaft with relation thereto, and oblique connecting rail lengths, a rail section extending from adjacent the sill of one, to adjacent the lintel of an adjacent, door opening, a switch mechanism, and a guide rail section extend- 115 120 125 130

ing from adjacent said switch mechanism to a point intermediate the sill and lintel of an adjacent door opening and positioned inwardly of the shaft with relation to said 5 other rail section, means carried by each of said door sections projecting across the edges of said wall angle, and across said rail sections and said switch mechanism respectively, flexible connections between said 10 means respectively, sheaves about which said flexible connections pass, the axes of said sheaves being parallel with the wall of the shaft adjacent the door opening, said wall angle adjacent the short and the oblique rail lengths of said first named rail section being cut away to permit movement of said means adjacent said rail lengths, guide shoes adjacent the top of the lower, and adjacent the bottom of the upper, door 15 sections co-operating with said first named rail section, a second guide shoe upon one of said sections co-operating with the rail section extending from adjacent the sill of one, to adjacent the lintel of an adjacent, door opening, and a second guide shoe upon the other door section co-operating with said switch mechanism and with the rail section adjacent thereto. 16. An elevator door embodying therein 20 upper and lower oppositely movable door sections, a rail structure on each side of the openings in an elevator shaft, each consisting of a wall angle extending vertically of the shaft and having secured thereto a rail section including therein a short rail length intermediate the sill and lintel of the door opening, long rail lengths parallel therewith positioned inwardly of the shaft with relation thereto, and oblique connecting rail lengths, a rail section extending from adjacent the sill of one, to adjacent the lintel of an adjacent, door opening, including a short rail length in substantially the same plane as said first named short rail length, a long rail length parallel therewith and in substantially the same plane as said first named long rail lengths, but spaced therefrom to form a gap, and an oblique connecting rail length, a switch mechanism between the lintel of one door opening and the sill of the opening above, comprising a guide flange adjacent the end of one of the long rail lengths of said first named rail section, and an abutment between the wall of the shaft and said guide flange and spaced therefrom, said guide flange and said abutment being so formed as to provide a channel therebetween, one end of which is directed across said gap, a guide rail section extending from adjacent said end of said channel to a point intermediate the sill and lintel of the adjacent door opening and positioned inwardly of the shaft with relation to said other rail sections, means carried by each of said door sections projecting across the edges of said wall angle, and across said rail sections and said switch mechanism respectively, flexible connections between said means respectively, sheaves about which said flexible connections pass, the axes of said sheaves being parallel with the wall of the shaft adjacent the door opening, said wall angle adjacent the short and the oblique rail lengths of said first named rail section being cut away to permit movement of said means adjacent said rail lengths, guide shoes adjacent the top of the lower, and adjacent the bottom of the upper, door sections co-operating with said first named rail section, a second guide shoe upon one of said sections co-operating with the rail section extending from adjacent 25 30 35 40 45 50 55 60 65

the sill of one, to adjacent the lintel of an adjacent, door opening, a second guide shoe upon the other door section co-operating with said switch mechanism and with the rail section adjacent thereto, stops carried by said wall angle in the path of movement of the means carried by the lower door section, and a truck bar carried by the top of said lower door section and projecting through the door opening when a door is closed. 70 75 80 85 90 95 100 105 110 115 120 125 130

17. An elevator door embodying therein upper and lower oppositely movable door sections, a rail structure on each side of the openings in an elevator shaft, each consisting of a wall angle extending vertically of the shaft and having secured thereto a rail section including therein a short rail length intermediate the sill and lintel of the door opening, long rail lengths parallel therewith positioned inwardly of the shaft with relation thereto, and oblique connecting rail lengths, a rail section extending from adjacent the sill of one, to adjacent the lintel of an adjacent, door opening, including a short rail length in substantially the same plane as said first named short rail length, a long rail length parallel therewith and in substantially the same plane as said first named long rail lengths, but spaced therefrom to form a gap, and an oblique connecting rail length, a switch mechanism between the lintel of one door opening and the sill of the opening above, comprising a guide flange adjacent the end of one of the long rail lengths of said first named rail section, and an abutment between the wall of the shaft and said guide flange and spaced therefrom, said guide flange and said abutment being so formed as to provide a channel therebetween, one end of which is directed across said gap, a guide rail section extending from adjacent said end of said channel to a point intermediate the sill and lintel of the adjacent door opening and positioned inwardly of the shaft with relation to said other rail sections, means carried by each of said door sections projecting across the edges of said wall angle, and across said rail sections and said switch mechanism respectively, flexible connections between said means respectively, sheaves about which said flexible connections pass, the axes of said sheaves being parallel with the wall of the shaft adjacent the door opening, said wall angle adjacent the short and the oblique rail lengths of said first named rail section being cut away to permit movement of said means adjacent said rail lengths, guide shoes upon said door sections each comprising spaced flanges having parallel faces adapted to co-operate with the short rail length and with a long parallel rail length, and parallel oblique faces adapted to co-operate with an oblique connecting rail length of said first named rail section, a second guide shoe on one of said door sections comprising oppositely dis-

- posed staggered parallel flanges having the adjacent ends thereof lapped, whereby the parallel faces thereof are adapted to co-operate with the parallel rail length, and the 5 lapped ends are adapted to co-operate with the oblique connecting rail length of the rail section extending from adjacent the sill of one door opening to adjacent the lintel of an adjacent door opening, and a long rail length 10 at an adjacent door opening, and a guide shoe upon the other door section comprising parallel spaced flanges, one of said flanges being projected laterally of the shoe and having a curved surface forming a flaring opening 15 for the space between said flanges, an inclined surface and a flattened end, and the other of said flanges having a substantially flat surface, and vertically and laterally extending curved surfaces, whereby said shoe is adapted 20 to engage the opposite walls of said channel forming means, and receive between same the rail length terminating adjacent the end of said channel.
18. An elevator door embodying therein upper and lower oppositely movable door sections, a rail structure on each side of the openings in an elevator shaft, each consisting of a wall angle extending vertically of the shaft and having secured thereto a 25 rail section including therein a short rail length intermediate the sill and lintel of the door opening, long rail lengths parallel therewith positioned inwardly of the shaft with relation thereto, and oblique connecting 30 rail lengths, a rail section extending from adjacent the sill of one, to adjacent the lintel of an adjacent, door opening, including a short rail length in substantially the same plane as said first named short 35 rail length, a long rail length parallel therewith and in substantially the same plane as said first named long rail lengths, but spaced therefrom to form a gap, and an oblique connecting rail length, a switch mechanism 40 between the lintel of one door opening and the sill of the opening above, comprising a guide flange adjacent the end of one of the long rail lengths of said first named rail section, and an abutment between the 45 wall of the shaft and said guide flange and spaced therefrom, said guide flange and said abutment being so formed as to provide a channel therebetween, one end of 50 which is directed across said gap, a guide rail section extending from adjacent said end of said channel to a point intermediate the sill and lintel of the adjacent door opening and positioned inwardly of the shaft with relation to said other rail sections, 55

means carried by each of said door sections 60 projecting across the edges of said wall angle, and across said rail sections and said switch mechanism respectively, flexible connections between said means respectively, 65 sheaves about which said flexible connections pass, the axes of said sheaves being parallel with the wall of the shaft adjacent the door opening, said wall angle adjacent the short and the oblique rail lengths of said first 70 named rail section being cut away to permit movement of said means adjacent said rail lengths, guide shoes upon said door sections each comprising spaced flanges having parallel faces adapted to co-operate with the short rail length and with a long 75 parallel rail length, and parallel oblique faces adapted to co-operate with an oblique connecting rail length of said first named rail section, a second guide shoe on one of said door sections comprising oppositely disposed staggered parallel flanges having the adjacent ends thereof lapped, whereby the parallel faces thereof are adapted to co-operate with the parallel rail length, and the lapped ends are adapted to co-operate 80 with the oblique connecting rail length of the rail section extending from adjacent the sill of one door opening to adjacent the 85 lintel of an adjacent door opening, and a long rail length at an adjacent door opening, a guide shoe upon the other door section comprising parallel spaced flanges, one of said flanges being projected laterally of the shoe and having a curved surface 90 forming a flaring opening for the space between said flanges, an inclined surface and a flattened end, and the other of said flanges having a substantially flat surface, and vertically and laterally extending curved 95 surfaces, whereby said shoe is adapted to engage the opposite walls of said channel forming means, and receive between same the rail length terminating adjacent the end of said channel, stops carried by said wall angle in the path of movement of the means 100 carried by the lower door section, and a truck bar carried by the top of said lower door section and projecting through the door opening when a door is closed.

In witness whereof I have hereunto affixed my signature, in the presence of two subscribing witnesses, this 6th day of December, 1922.

ROBERT S. PEELE.
